ELECTROLYTIC CONDENSER

Eric C. Wahlberg, Plainfield, N. J.

Application March 9, 1939, Serial No. 260,816

5 Claims. (Cl. 175—315)

My invention relates to electric circuits, and has among its objects and advantages the provision of an improved electrolytic condenser.

An object of my invention is to provide an electrolytic condenser embodying anodes of the film forming type in combination with a cathode in the nature of a container wherein novel means are incorporated for isolating a plurality of anodes in a common container to the end that the 5 unit will embody a plurality of anodes. The anodes are grouped in a unitary structure in the nature of an insert which may be incorporated in the container or cathode. While the anodes comprise distinct and separate elements, means 10 are employed for fixedly relating the anodes in a compact and sturdy manner so as to provide a unit which may easily be incorporated in the container.

A further object is to provide a condenser of 20 the type described embodying a container terminating in a bored neck together with a plurality of anodes grouped as a unit and provided with individual tabs for connection with the electric circuits in which the tabs are grouped about a 25 common support extending through the bore in the neck. A resilient sleeve is interposed between the wall of the bored neck and the grouped tabs for consummating an effective seal between the 30 parts in addition to lending support thereto. The resilient sleeve renders the related parts liquid tight and is so constructed as to compensate variation in the structural parts associated therewith.

Another object is to provide an electrolytic condenser embodying a container or cathode provided with a closure cap together with novel means for effectively sealing the cap and the container. Between the cap and the container I 40 provide a resilient gasket and shape the parts so as to provide an effective seal through contraction of one part upon the others. The cap embodies a perforated dome-shaped element for venting purposes and the gasket is provided with a vent opening communicating with the dome-shaped element.

Another object is to provide an electrolytic condenser embodying a plurality of anodes in which novel means are incorporated for isolating the 50 anodes wherein a liner is incorporated in the container or cathode housing the anodes. Separators of insulating material are arranged to individually isolate the anodes inside the container and the separators for close fitting relation with 55 the liner of the container, with the liner per-

forated or slotted so as to expose the container to the electrolyte.

Another object is to provide an electrolytic condenser so constructed as to facilitate substitution of parts without damage to the intact 5 parts.

In the accompanying drawing:

Figure 1 is a sectional view of an electrolytic condenser in accordance with my invention;

Figure 2 is a sectional view along the line 2—2 10 of Figure 1;

Figure 3 is a view similar to Figure 1 but illustrating the plane of the section rotated 45 degrees;

Figure 4 is a sectional view along the line 4—4 15 of Figure 1;

Figure 5 is a sectional view of the bushing about which the tabs of the anodes are grouped and supported;

Figure 6 is a sectional view along the line 6—6 20 of Figure 5;

Figure 7 is a fragmentary perspective view of one of the anodes;

Figure 8 is a sectional view along the line 8—8 25 of Figure 3; and

Figure 9 is a fragmentary perspective view of the liner which fits inside the container or cathode.

In the embodiment selected to illustrate my invention, the unit 10 includes four filmed anodes 30 or positive electrodes 12 enclosed within a container 14 common to the four anodes. The container 14 is formed of suitable non-filmed material having conducting properties and constituting the negative electrode or cathode. The 35 anodes 12 are immersed in the electrolyte, as for example a solution of borax and boric acid, contained in the container 14. The anodes 12 may comprise aluminum foil having tabs 16 extending exteriorly of the container for connection with 40 the external circuit or circuits and are insulated from each other.

Figure 7 illustrates the greater part of one of the anodes 12, and since all the anodes are similarly constructed, the description of one will 45 apply to all. According to Figure 7, the anode comprises a thin sheet of metal bent to provide deep corrugations 18 which are radially arranged with respect to the axis of the container and extend longitudinally thereof, as illustrated in 50 Figure 2. Corrugations 18 are concentrically related about the axis of the container, and the sheet comprising the anode is folded back upon itself at 20, see Figure 2, to provide a connection between the overlapping and folded margins of 55

the sheet. The anodes 12 extend substantially the full length of the container 14, and each anode is cut along the lines 22 adjacent the folds 20 and transversely at 24 with the material inside the slots bent back at 26 to provide arms 28 extending longitudinally of their respective anodes. According to Figure 7, the arm 28 extends beyond the lower end 30 of the anode 12 and is fixedly connected at 32 with the associated tab 16. Connection 32 comprises wings 34 bent back upon themselves for embracing the arm 28 and provided with teeth 36 which are struck into the material of the arm for effecting a fixed connection.

15 Container 14 includes a bottom 38 terminating in a neck 40 threaded at 42 for connection with a suitable support. I provide the neck 40 with a tapered bore 44, the taper of which decreases in the direction of the lower end of the neck. Inside the container 14 I mount a disc 46 of insulating material, which disc includes an integral shank 48 extending through the bored neck 40. Between the wall of the bore 44 and the shank 48 I interpose a tapered sleeve 50 of resilient material such as rubber. Referring to Figure 5, the shank 48 is grooved at 52 and 54 for receiving the arms 28 and tabs 16, respectively. Each groove 52 is interconnected with its associated groove 54 by an enlarged groove 56 of sufficient size to house the connection 32 associated therewith. Arms 28 and the tabs 16 are pressed into their respective grooves so as to have tight fitting relation with the walls of the grooves. At the same time, the disc 46 is perforated at 58 for accommodating the arms 28.

Figure 1 illustrates the lower ends of the tabs 16 as extending beyond the shank 48 for connection with their respective circuits. Sleeve 50 has its upper end extending slightly above the bottom 38 so as to be engaged by the disc 46. A washer 60 of insulating material is positioned adjacent the lower end of the neck 40 and a nut 62 of insulating material has threaded relation with the threaded reach 64 of the shank 48. Thus the disc 46 will press the tapered sleeve 50 into the tapered bore 44 when the nut 62 is tightened. Such tightening of the nut 62 will press the resilient sleeve 50 firmly against the arms 28 and the tabs 16 so as to provide a liquid tight seal between the sleeve and the bore 44 as well as between the sleeve and the arms 28 and the tabs 16.

Inside the container 14 I position a close fitting liner 66 of insulating material. This liner is in the nature of an open ended tube having four columns of slots 68. Liner 66 extends from the bottom 38 to a point slightly above the upper ends of the anodes 12. Two separating sheets 70 of insulating material are arranged in crossed relation inside the liner 66 to provide four chambers 72 each housing one of the anodes 12. Sheets 70 are each slotted inwardly of one of their ends, as at 74, half their length and interfitted as illustrated in Figure 3 so that the sheets have interlocking connection at the axis of the container 14. The outer edges of the sheets 70 are pressed against the liner 66 and the sheets are so arranged as to position one column of slots 68 within each of the chambers 72. Disc 46 is provided with spaced ribs 76 to provide grooves 78 within which the lower ends of the sheets 70 are positioned for support.

The disc is spaced slightly from the bottom 38, as at 80 and the disc is provided with openings 82 grouped within the chambers 72, see Figure 4.

The peripheral face of the disc fits snugly inside the liner 66.

Tapered sleeve 50 includes a ring 102 and connecting bands 104 which lie underneath the disc 46, with the bands 104 so arranged as to provide a separate chamber under each of the groups of openings 82. These chambers are sealed one from the other when the disc is drawn down.

The upper end of the container 14 is closed by a cap 84 which is struck up at 86 and provided with a perforation 88 for venting purposes. Cap 84 is provided with a curved flange 90 terminating in an outwardly projecting flange 92. Adjacent the inner face of the cap 84 I position a gasket 94 of material such as rubber, which is flanged at 96 to embrace the flange 90. Cap 84 is positioned according to Figure 1 and the upper end of the container 14 is spun to contract the end against the flange 96 of the sealing gasket so as to provide a firm connection. Flange 92 is so related to the flange 90 as to provide a trough 98 within which the end of the container 14 is positioned so as to restrain the cap from relative movement longitudinally of the container. At the same time, the cap construction is such as to permit the container 14 to be contracted firmly upon the gasket lined cap so as to provide a liquid tight seal. Gasket 94 is provided with a small perforation 100 for venting purposes, which perforation is aligned with the dome-shaped element 86.

It will thus be seen that the container 14 provides a housing for a plurality of anodes, which anodes are isolated through the medium of the walls or sheets 70. Liner 66 insulates the anodes 12 from the container in case of accidental displacement of the anodes, but the construction of the liner is such as to expose considerable area of the container 14 to the electrolyte. Space 80 between the disc 46 and the bottom 38 provides accommodation for solids precipitated from the electrolyte.

I claim:

1. An electrolytic condenser comprising a plurality of anodes each having a connection element, a common cathode in the nature of a container for a common electrolyte, separator means between the anodes, said container having a tapered bore and said connection elements extending through the tapered bore, a shank extending through said tapered bore and having a disc located inside the container, said shank having grooves for partly housing said connection elements, resilient means positioned inside said tapered bore and encircling said shank and the connection elements in said grooves, one end of said resilient means engaging said disc, and means threadedly connected with said shank and coacting with the container for drawing the disc against said resilient means for compressing the latter tightly about said shank and said connection elements.

2. An electrolytic condenser comprising a plurality of anodes each having a connection element, a common cathode in the nature of a container for a common electrolyte, separator means between the anodes, said container having a mounting neck provided with a tapered bore, said connection elements extending through said tapered bore, a shank extending through said tapered bore and having a disc located inside the container closely adjacent said neck, said shank having longitudinal grooves for partly housing said connection elements, resilient means positioned inside said tapered bore and encircling

- 5 said shank and the connection elements in said grooves, one end of said resilient means engaging said disc, and means threadedly connected with said shank and coacting with said neck for drawing said disc against said resilient means to compress the latter tightly against the wall of said bore and about said shank and said connection elements.
- 10 3. An electrolytic condenser comprising a plurality of anodes each having a connection element, a common cathode in the nature of a container for a common electrolyte, separator means between the anodes, said container having a mounting neck provided with a tapered bore, said
- 15 connection elements extending through said tapered bore, a shank extending through said tapered bore and having a disc located inside the container closely adjacent said neck, said shank having longitudinal grooves for partly housing said connection elements, resilient means positioned inside said tapered bore and encircling said shank and the connection elements in said grooves, one end of said resilient means engaging said disc, means threadedly connected with said shank and coacting with said neck for drawing 10 said disc against said resilient means to compress the latter tightly against the wall of said bore and about said shank and said connection elements, a perforated non-conducting liner inside the container, said separator means comprising non-conducting sheets arranged in crossed and interlocking relation to provide individual spaces for the anodes, the perforations in the liner being arranged in the form of columns located within the spaces defined by the 20 separator means, grooves in said disc for partly receiving said separator means to support the sheets thereof in predetermined spaced relation, said disc being provided with perforations grouped within said spaces, and sealing means 25 between the disc and the end of the container adjacent said neck to seal the groups of perforations in the disc one from the other.
- 25 4. An electrolytic condenser comprising a plurality of anodes each having a connection element, a common cathode in the nature of a container for a common electrolyte, separator means between the anodes, said container having a mounting neck provided with a tapered bore, said
- 30 connection elements extending through said tapered bore, a shank extending through said tapered bore and having a disc located inside the container closely adjacent said neck, said shank having longitudinal grooves for partly housing said connection elements, resilient means positioned inside said tapered bore and encircling said shank and the connection elements in said grooves, one end of said resilient means engaging said disc, means threadedly connected with said shank and coacting with said neck for drawing 10 said disc against said resilient means to compress the latter tightly against the wall of said bore and about said shank and said connection elements, a perforated non-conducting liner inside the container, the perforations in the liner being arranged in the form of columns located between the separator means to be respectively grouped with said anodes, and means on said disc acting upon said separator means for supporting the same in predetermined relative positions.
- 35 5. In an electrolytic condenser, an anode comprising a sheet of foil having deep corrugations and bent to hollow formation longitudinally of said corrugations, with said corrugations paralleling one another, said foil having overlapping edge margins each bent back upon itself and interconnected with the other edge margin, said foil being slit part way of its length along the overlapping edge margins and transversely thereof intermediate the ends of the foil, and the overlapping edge margins within the slits being bent outwardly and downwardly to provide a connection tab.
- 40 ERIC C. WAHLBERG.
